UNITED STATES PATENT OFFICE.

MILTON C. J. BILLINGHAM, OF KALAMAZOO, MICHIGAN.

PAPER-STOCK-TREATING MACHINE.

1,420,362.

Specification of Letters Patent. Patented June 20, 1922.

Application filed September 1, 1920. Serial No. 407,468.

To all whom it may concern:

Be it known that I, MILTON C. J. BILLINGHAM, a citizen of the United States, residing at Kalamazoo, county of Kalamazoo, State of Michigan, have invented certain new and useful Improvements in Paper-Stock-Treating Machines, of which the following is a specification.

This invention relates to improvements in paper stock treating machines.

My improved stock treating machine is especially designed by me for use in disintegrating old paper for use as paper stock and for deinking such stock.

The main objects of this invention are:

First, to provide an improved disintegrating or defibering machine in which the fibers are effectively separated without grinding action.

Second, to provide an improved disintegrating or defibering machine well adapted for the treatment of printed papers and deinking the same and preparing the same for paper stock which produces a superior product.

Further objects and objects relating to structural details will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this specification, in which:

Fig. I is a detail view partially in vertical central section of a stock treating machine or apparatus embodying the features of my invention.

Fig. II is an inverted view of the perforated disintegrating plate.

In the accompanying drawing, I have not attempted to illustrate or maintain the proper relative proportions of parts as these will be varied to suit the capacity and the particular conditions of installation of the machines and I also show various parts in conventional form.

In the embodiment illustrated I provide a cylindrical tank 1 disposed vertically and provided with an internally concave bottom 2 and a curved top 3 having a central man-

hole 4 therein. This manhole is provided with a cover 5, the attaching means for the cover being shown conventionally at 6.

The tank has a central discharge indicated by dotted lines at 7. The discharge pipe 8 of the tank is connected to the inlet 9 of the pump 10. The supply connection 11 is provided for the stock to be treated. This connection is controlled by the valve 12, the pipe 8 being provided with a valve 13.

The pump discharge 14 is provided with a discharge connection 15 for the treated stock controlled by the valve 16, and with a discharge pipe 17 disposed centrally through the openings 7 in the tank and having a nozzle 18 at its upper end delivering near the top of the tank and centrally thereof.

A foraminated concave plate 19 is supported above the nozzle so that the stream from the nozzle strikes the plate. The plate 19 is suspended from the manhole cover 5 by means of the hangers 20. The holes 21 in the plate 19 are preferably tapered as illustrated.

The pump is driven from an electric motor indicated at 22.

With the parts thus arranged the stock to be disintegrated is delivered from the nozzle 18 against the plate 19 and is driven through the holes in the plate so that the fibers are pulled apart and separated, the stock being circulated as long as may be desired.

My improved disintegrating or defibering machine is not likely to clog as any pieces of string or the like which strike the plate fall back into the tank and further the stream impinges against the plate forcibly driving the stock through it keeping the openings comparatively free. The upper walls of the tank are curved so that the stock is deflected downwardly within the tank around the walls and this insures a complete circulation of the stock which is of importance as should a portion fail to circulate for a time and then become lodged, the stock is not uniformly disintegrated and is not suitable for the purposes intended.

My improved machine is especially well adapted for treating stock with a deinking solution as the stock is effectively disintegrated and uniformly treated.

I have illustrated but one adaptation or embodiment of my improvements as I be-

lieve that that will enable those skilled in the art to which my invention relates to embody or adapt the same as may be desired.

Having thus described my invention what I claim as new and desire to secure by Letters Patent is:

1. In a stock treating machine, the combination of a vertically disposed cylindrical tank having an internally concave bottom 10 with a central discharge opening therein and an internally curved top having a centrally located manhole therein, a cover for said manhole, a pump having its intake connected to said tank discharge, a discharge pipe for 15 said pump disposed through said discharge opening centrally and vertically of said tank and provided with a discharge nozzle positioned at the upper end of the tank, and a horizontally disposed concave foraminated 20 plate suspended from said manhole cover above said nozzle to receive the stream therefrom.
2. In a stock treating machine, the combination of a vertically disposed cylindrical 25 tank having an internally concave bottom with a central discharge opening therein, a pump having its intake connected to said tank discharge, a discharge pipe for said pump disposed through said discharge opening centrally and vertically of said tank and provided with a discharge nozzle positioned at the upper end of the tank, and a horizontally disposed concave foraminated plate disposed above said nozzle to receive the 30 stream therefrom.
3. In a stock treating machine, the com- 35

bination of a tank having a discharge at the bottom, a pump having its intake connected to said discharge, a discharge pipe for said pump disposed vertically of said tank 40 through said discharge opening, and a horizontally disposed foraminated member disposed above and in a spaced relation to the end of said discharge pipe to receive the stream therefrom. 45

4. In a stock treating machine, the combination of a tank having a discharge at the bottom, a circulating pump, a discharge pipe for said pump delivering within said tank, and a foraminated member disposed in 50 alignment with the stream delivered by the pump, all coacting for the purpose specified.

5. In a stock treating machine, the combination of a tank, a stock circulating pump connected to the bottom of the tank and provided with a discharge nozzle within said tank, and a concave foraminated plate disposed transversely of said nozzle to receive the stream therefrom. 55

6. In a stock treating machine, the combination of a tank, a stock circulating pump connected to the bottom of the tank and provided with a discharge within said tank, and a foraminated member disposed to receive the stream from said discharge. 60 65

In witness whereof, I have hereunto set my hand and seal in the presence of a witness.

MILTON C. J. BILLINGHAM. [L. S.]

Witness:

GRACE B. THOMPSON.
